UNITED STATES PATENT OFFICE.

JOHN N. PETERSON, OF MILWAUKEE, WISCONSIN, ASSIGNOR OF ONE-HALF TO CHARLES F. ZANZIG, OF MILWAUKEE, WISCONSIN.

BOBBIN-WINDING MECHANISM.

1,308,529.

Specification of Letters Patent.

Patented July 1, 1919.

Application filed April 1, 1918. Serial No. 225,967.

To all whom it may concern:

Be it known that I, JOHN N. PETERSON, a citizen of the United States, and resident of Milwaukee, in the county of Milwaukee, 5 and State of Wisconsin, have invented certain new and useful Improvements in Bobbin-Winding Mechanism; and I do hereby declare that the following is a full, clear, and exact description thereof.

10 My invention refers to improvements in sewing machines and other machines using bobbins or spools of thread, and more particularly to means for rewinding bobbins and spools or the like for use in such machines.

In devices of this general character at present in use a considerable amount of thread is wasted in addition to the fact that the mechanisms are slower in operation and 20 otherwise less efficient. One of the objects of the present invention is, therefore, to provide a bobbin winding mechanism which will be semi-automatic, or automatic to the extent that the operation ceases when a pre-determined amount of thread has been wound upon the bobbin, and simultaneously with the cessation of the winding operation the thread will be severed. The provision of such simultaneous action saves approximately 25 six inches of thread in each winding, and as many bobbins are wound during the day's work, it is obvious this saving amounts in a short time to quite a considerable extent.

30 An additional object is to provide an improved and simply constructed means for holding the bobbin releasably, yet tightly, in engagement with the main operating shaft.

40 With these and other objects and advantages in view the invention resides in the novel features of construction, combination and arrangement of parts which will be hereinafter more particularly described and 45 claimed and shown in the drawings, wherein:

Figure 1 represents a side elevational view, partly in section, of a bobbin winding mechanism constructed in accordance with my invention.

50 Fig. 2 is a vertical transverse sectional view taken substantially on the plane of the line 2-2 of Fig. 1.

Fig. 3 is a vertical sectional view on the plane of the line 3-3 of Fig. 2.

Fig. 4 is a horizontal sectional view on 55 the plane of the line 4-4 of Fig. 1, and Fig. 5 is an enlarged detail sectional view on the line 5-5 of Fig. 1.

In practice my invention is adapted to be mounted adjacent the usual drive belt B of 60 a sewing machine or machine of like nature. The operating parts of the invention are all carried by a suitable support which includes a horizontally disposed base plate 1, and a vertical plate 2, one end of which is spaced 65 from one end of the base plate, said vertical plate having a laterally extending flange 3 beneath which the thread T which is to be wound is adapted to run. The flange 3 thus prevents articles from being laid across 70 the support in such a manner as to be entangled with the thread. The up-right plate 2 has oppositely extending attaching feet 4 whereby the support may be secured to the top of a sewing machine or the like. 75

A bobbin 5 to be filled with thread is disposed upon the stub end 6 of a shaft 7 to which a drive pulley is keyed or otherwise fixed, said pulley being grooved for engagement by the drive belt B. This shaft 80 7 is journaled in a bearing 9 formed on the upper end of a swinging arm 10, the lower end of which is bifurcated to provide ears 11. Said ears are provided with apertures which align with apertures formed in fixed 85 spaced ears 12 which extend from the base plate 1 as best disclosed in Fig. 2; a pivot pin 13 is extended through said aligned apertures. By this arrangement the pulley 8 may be swung toward or away from the 90 drive belt B, and when spaced therefrom is obviously inoperative.

The pulley 8 and its supporting swinging arm is held in operative position by the engagement of a latch finger 14, carried by 95 the end of a pivoted flexible latch plate 15, with a catch 16 extending from the bearing 9. The latch plate 15 is pivoted to the upright plate 2 at its end remote from the latch finger 14, said finger being extended 100 beyond the end of said plate 2 and over the base plate 1. In moving the swinging arm 10 toward the latch plate, said finger 14 will engage and ride on a cam 17 which terminates at the catch 16. 105

When the parts are held in this operative position by the latch finger 14 and the catch 16, the bobbin 5 is frictionally held against

independent rotative movement with respect to the shaft 7 by the engagement of the peripheral edge of one side flange 5' with the concave face of a friction disk 18, said disk 5 being preferably formed of leather and disposed against the concave side of a concavo-convex plate 19 which is secured to the shaft 7. Longitudinal movement of the bobbin, while the winding mechanism, including the 10 pulley 8 and the swinging arm 10, is moved from inactive to operative position is obviated by the engagement of a spherical spring pressed detent 20 in an annular groove 21 formed in the inner wall of the cylindrical body of said bobbin, said detent being positioned in a socket in the stub end 6 of said shaft 7.

Additional stationary retaining means is 20 also provided for holding the bobbin for rotation with the shaft 7, said means being adapted to coöperate with the friction disk 18. This means includes a cylindrical detent carrying casing 22 adjustably secured to a bracket 23 carried by the up-right plate 2 and disposed for longitudinal axial alignment with the shaft 7 when the same is in operative position, said casing containing a spherical detent 24 which is caused to extend through an opening in one end by reason of an expansile spring 25. The projecting portion of the detent 24 is adapted to engage in the hollow body of the bobbin 5 as shown in Fig. 5, the stub end of said shaft 6 being of slightly less length than that of 30 the body of the bobbin to permit this engagement between the latter and said detent 24. As hereinbefore mentioned this invention includes means for automatically releasing the winding mechanism from the 40 drive belt B after a predetermined amount of thread has been disposed on the bobbin 5. Therefore, a releasing arm 26 is secured to the free end of the latch plate 15 and carries a roller 27 for engagement with the thread 45 on the bobbin. An expansile spring 28 engaged with said latch plate normally retains the roller 27 in contact with said thread and the latch finger 14 in coöperation with the catch 16, and thus as the thread on the bobbin 50 increases in amount, the releasing arm is raised upwardly against the tension of the spring, and finally the latch finger and its catch are disengaged. Upon said disengagement an expansile spring 29 will force the 55 swinging arm 10 to inactive position as indicated in Fig. 1. The tension of the drive belt B will aid the spring 29 in the return movement of the winding mechanism. Inasmuch as the winding mechanism is thrown 60 to its inactive position with considerable force, a bumper 30 of resilient material is secured to the base plate 1 in position to be engaged by the pulley 8.

Simultaneously with the movement of the 65 winding mechanism to its inoperative posi-

tion, the thread T is severed at a point close to the bobbin 5. For this purpose the swinging arm 10 carries a reciprocatory hooked cutting blade 31 which is moved across the path of movement of the thread by the rocking of a bell crank lever 32, to one arm of which it is connected by a pin 33. Said cutting blade 31 is slidably guided in a groove 34 cut in the swinging arm 10 and in which it is held by a plate 35, the latter being secured as at 36 to said arm 10; a slot 37 in the plate 35 allows for the movement of the pin 33.

The bell crank lever is operated by a lever actuating plate 38 pivoted at one end as 39 80 to the base plate 1 and loosely attached at its other end to the upper end of the swinging arm 10. It will be noted that the pivots of the arm 10 and the plate 38 are spaced apart. The plate 38 is provided with a pair of spaced shoulders 40 and 40' between which the arm 41 of the bell crank lever 32 is disposed.

The thread T may be fed to the bobbin in any desired manner, but is preferably guided as shown most clearly in Figs. 1 and 4 wherein 42 and 43 represent a pair of spaced L-shaped guide rods secured to the up-right plate 2 and having their free ends positioned in notches 44 cut in the flange 3. Said flange 90 also has a guide opening 45 through which the thread is fed from a spool 46 or from any other suitable source. Between the guide rods 42 and 43 is disposed a thread straightener 47 of usual design. These elements are at the end of the support remote from the winding mechanism and the thread is guided at the other end, particularly adjacent the end of the up-right plate 2, between a pair of spaced depending fingers 48 105 that extend from the free end of the latch plate 15. Said thread also runs over a wear plate 49 secured to the bracket 23 and is clamped against the same by a retaining strip 50 carried by the latch plate when the latter is disengaged from the winding mechanism. This holds the thread taut after being severed so that the same will be in position to be connected with a bobbin.

The operation can be readily seen from 115 the several figures of the drawings taken in connection with the accompanying description, but is briefly set forth as follows:— Assuming that the parts are arranged as in Fig. 1 with the thread T disposed through 120 the several guiding devices, the free end of said thread is positioned between the inner flange 5' of the bobbin and the friction disk 18 to connect the same with said bobbin. The winding mechanism is then swung toward the right to engage the pulley 8 with the belt B and connect the latch finger 14 with its catch 16.

When the winding member was in inactive 130 position the reciprocatory cutting blade 31

was in retracted position inasmuch as the shoulder 40' was in engagement with the arm 41 to hold the latter in lowered position. When, however, the winding mechanism is moved into operative position the other shoulder 40 engages and raises the arm 41 and therefore throws the cutting blade to its extended position as in Fig. 2.

The parts remain in this operative position until sufficient thread has been wound on the bobbin to raise the latch plate to release the catch 16, whereupon said swinging arm 10 will move outwardly as hereinbefore mentioned. Simultaneously therewith the cutting blade will be retracted owing to the engagement of the shoulder 40' with the arm 41 of the bell crank lever and the thread T severed.

Various minor changes may be made in the form and proportion of the several parts of the invention without departing from or sacrificing any of the principles thereof as set forth in the following claims.

I claim:—

1. A bobbin winding mechanism including a support, a carriage movable on the support and resiliently urged to movement in one direction, a latch member urged for engagement with the carriage to hold it against movement, a bobbin shaft on the carriage, a drive member on the shaft, means for releasing the carriage from the latch member, and means operable by release of the carriage from the latch member for clamping thread adjacent the carriage.

2. A bobbin winding mechanism including a support, a carriage movable on the support and resiliently urged to movement in one direction, a latch member urged for engagement with the carriage to hold it against movement, a bobbin shaft on the carriage, a drive member on the shaft, means for releasing the carriage from the latch member, a frictional thread holding means on the support remote from the carriage, and means operable by release of the carriage from the latch member for clamping thread adjacent the carriage.

3. A bobbin winding mechanism including a support, a carriage movable on the support and resiliently urged to movement in one direction, a latch member resiliently urged for engagement with the carriage to hold it against movement, a bobbin shaft on the carriage, a drive member on the shaft, means for releasing the carriage from the latch member, a clamping portion on the latch member, and a clamping member carried by the support and engageable by the clamping portion of the latch member upon release of the carriage from the latch member for clamping thread between said clamping portion and clamping member.

4. A bobbin winding mechanism including a support, a carriage movable on the

support, a bobbin shaft on the carriage, a drive member on the shaft, means resiliently urging the carriage to movement in one direction, means for holding the carriage against such movement, means operable by the amount of thread wound on a bobbin on the shaft for releasing said holding means, means operable coincident to release of the carriage for clamping thread thereadjacent, and means operable upon release of the carriage for cutting thread between the bobbin and said clamping means.

5. A bobbin winding mechanism including a support, a carriage movable on the support and resiliently urged to movement in one direction, a bobbin shaft on the carriage, a drive member on the shaft, a knife mounted on the carriage and movable relative to the carriage to procure cutting action and means operable by movement of the carriage for moving the knife relative to the carriage for cutting thread adjacent the bobbin.

6. A bobbin winding mechanism including a support, a carriage movable on the support and resiliently urged to movement in one direction, a bobbin shaft on the carriage, a drive member on the shaft, a knife slideable on the carriage, a lever on the carriage engageable with said knife for moving the knife to cut thread adjacent the bobbin, and a member on the support and engageable by the lever upon movement of the carriage for moving said knife relative to the carriage.

7. A bobbin winding mechanism including a support, a carriage movable on the support and resiliently urged to movement in one direction, a bobbin shaft on the carriage, a drive member on the shaft, a knife transversely slideable on the carriage, an angle lever having one arm connected with the knife for sliding said knife to cut thread adjacent the bobbin, and a member on the support and engageable with the other arm of the angle lever for sliding the knife.

8. In a bobbin winding mechanism, a support, a carriage pivotally mounted on the support, a bobbin shaft on the carriage, a drive member on the shaft, and a knife slideable on the carriage, an angle lever pivoted on the carriage and having one end connected with the knife for procuring sliding movement of the knife to cut thread adjacent the bobbin, a bar pivoted on the support adjacent the carriage and slidably connected with the carriage, and stops on the bar engageable with the other arm of the angle lever.

9. A bobbin winding mechanism including a support, a carriage mounted on the support for movement toward and away from a certain drive position, a bobbin shaft on the carriage, a drive member on the bobbin shaft, and a detent member mounted on the support for opposition to one end of the

shaft in drive position of the carriage for holding a bobbin on the shaft in such drive position of the carriage.

10. A bobbin winding mechanism including a support, a carriage mounted on the support for movement toward and away from a certain drive position, a bobbin shaft on the carriage, a drive member on the bobbin shaft, a bobbin stop on the shaft adjacent one end thereof, and a yieldably mounted holding member mounted on the support for opposition to the shaft end in drive position of the carriage for engagement in the bore of a bobbin on the shaft end in drive position of the carriage.

11. A bobbin winding mechanism including a support, a carriage mounted on the support for movement toward and away from a certain drive position, a bobbin shaft 20 on the carriage, a drive member on the bobbin shaft, a bobbin stop on the shaft adjacent one end thereof, a yieldably mounted holding member mounted on the support for opposition to the shaft end in drive position

of the carriage for engagement in the bore 25 of a bobbin on the shaft end in drive position of the carriage, and a bobbin engaging friction face on the stop member.

12. A bobbin winding mechanism including a support, a carriage mounted on the support for movement toward and away from a certain drive position, a bobbin shaft 30 on the carriage, a drive member on the bobbin shaft, a casing mounted on the support and provided with an opening disposed for 35 axial alignment with the bobbin shaft in drive position of the carriage, a ball in the casing adapted to partially project through the opening for yieldable engagement in the bore of a bobbin mounted on the shaft, and 40 a spring in the casing urging said ball to project through the opening.

In testimony that I claim the foregoing I have hereunto set my hand at Milwaukee, in the county of Milwaukee, and State of Wisconsin.

JOHN N. PETERSON.
